UNITED STATES PATENT OFFICE.

GEORGE T. BUDDLE, OF CHICAGO, ILLINOIS.

COMBINATION TABLE LOCK AND OPENER.

1,262,919.

Specification of Letters Patent. Patented Apr. 16, 1918.

Application filed May 23, 1917. Serial No. 170,502.

To all whom it may concern:

Be it known that I, GEORGE T. BUDDLE, a citizen of the United States, residing at Chicago, in the county of Cook and State of

5 Illinois, have invented a new and useful Combination Table Lock and Opener, of which the following is a specification.

This invention relates to combination table locks and openers, one of its objects 10 being to provide a simple device which can be fastened readily to the bottom faces of the end sections of an extension table and which when shifted in one direction will draw the sections together tightly and hold 15 them so that they cannot pull apart until the operating member of the device is first shifted. A further object is to provide a device of this character which, when moved in one direction will not only unlock the two 20 table sections, but will also move them apart so that it becomes an easy matter thereafter to further extend the table.

A still further object is to simplify and otherwise improve upon the construction of 25 devices of this character such as heretofore used and one of which has been shown, for example, in Patent No. 1,103,029, issued to me on July 14, 1914. Heretofore it has been necessary to utilize stop devices provided 30 especially for limiting the movement of the parts. It is an object of the present invention to do away with special stop devices and utilize as stops certain parts having other 35 functions, thereby materially reducing the cost of producing the device.

With the foregoing and other objects in view which will appear as the description proceeds, the invention resides in the combination and arrangement of parts and in 40 the details of construction hereinafter described and claimed, it being understood that changes in the precise embodiment of the invention herein disclosed, can be made within the scope of what is claimed, without 45 departing from the spirit of the invention.

In the accompanying drawings the preferred form of the invention has been shown. In said drawings:

Figure 1 is a bottom plan view of a portion 50 of an extension table having the present improvements combined therewith, the sections being shown separated.

Fig. 2 is a similar view showing the table sections drawn together and locked.

55 Fig. 3 is a section on line 3—3 of Fig. 2. Referring to the figures by characters of

reference, A and B designate the relatively movable sections of the top of an extension table. Secured to the bottom of the section B so as to project slightly beyond the inner 60 edge thereof is a plate 1 having an ear 2 extending downwardly therefrom. Another plate 3 is secured to the section A close to the inner edge thereof and is held thereto by obliquely disposed screws 4, the heads of 65 which project downwardly below the surface of the plate and constitute stops for a shifting lever 5 which is pivotally mounted on a stud 6 extending from the plate. One end of this lever projects beyond the inner 70 edge of the section A and has a shifting cam 7 projecting therefrom at one side. This cam is spaced from a curved gripping tongue 8 so that an arcuate slot 9 is thus provided between the cam and the tongue. The parts 75 are so proportioned that when the lever 5 is bearing laterally against the stops 4 the end of the cam 7 is held in the path of one side portion of the ear 2 while the end of the tongue 8 is removed from the path of said 80 ear.

A plate 10 the middle portion of which is preferably offset downwardly as indicated at 85 11 is secured to the bottom face of the section A at points removed from the plate 3. Extending from this plate is a pivot stud 12 having a head 13 above and engaging the offset portion 11 of the plate, and mounted on this stud is a handle lever 14. That portion of the stud projecting below the handle 90 lever is enlarged to constitute a stop 15. Pivotally connected to the handle lever is one end portion of a link 16 the other end portion of which is pivotally attached as at 17 to the lever 5. This link 16 is offset near 95 its ends as indicated at 18 so as to be capable of stretching and contracting to a limited extent.

The pivot connecting the link 16 to the handle lever 14 has been indicated at 19 and 100 extending from the link close to this pivot is a finger 20 adapted to move laterally against the stop portion 15 of the stud 12 and thus limit the relative movement of the handle lever and the link when said lever is moved 105 in one direction. The parts are so proportioned that the finger 20 will not engage the stop 15 until after the pivot 19 has passed the dead center between the pivots 17 and 15. See Fig. 2. With the parts positioned 110 as shown in Fig. 1, it will be apparent that when the sections A and B are moved toward

each other the ear 2 will come against the cam 7 as shown. By then pulling the handle lever 14 in the direction indicated by the arrow in Fig. 1, the tongue 8 will be caused 5 to swing into position back of the ear 2 and pull said ear toward the section A with the result that section B will be pulled against the section A. Continued movement of the handle lever 14 will cause the link 16 to 10 slightly buckle until the pivot 19 has passed the dead center and the finger 20 has come against the stop portion 15, whereupon the parts will be securely locked and the sections cannot be pulled apart unless the movement of the handle lever 14 is reversed. During this reverse movement the cam 7 will 15 press against the ear 2 and thrust the section B away from the section A until the parts assume the relative positions shown in Fig. 1.

20 Importance is attached to the fact that the lever 14 is provided with two arms one of which constitutes the handle while the other arm carries the pivot 19. This arrangement gives a greater leverage than has heretofore 25 been possible in the practical table lock of the same type.

What is claimed is:

1. The combination with relatively movable table top sections and an ear projecting 30 downwardly from one of the sections, of an attaching plate secured to the other section, combined fastening means and stops engaging the plate, a shifting lever pivotally mounted on said plate and limited by said

stops, a cam projecting from one end of the 35 lever, an arcuate tongue extending from said end of the lever, said tongue and cam being separated by an arcuate ear receiving slot, a handle lever, means for attaching the same to a top section, and a link connection between the two levers. 40

2. The combination with relatively movable table top sections and an ear projecting from one of the sections, of plates secured to the other section, combined fastening and 45 stop devices engaging one of the plates, a shifting lever pivotally connected to said last named plate, a cam projecting from one end of the lever, an arcuate tongue extending from said end of the lever, the tongue and 50 cam being spaced by an ear receiving slot, a handle lever, a pivot stud extending from the other plate and through the handle lever, and having an enlarged terminal forming a stop portion, a link offset between its ends 55 and pivotally connected to the two levers, and a stop finger upon the link and movable against said stop portion when the pivotal connection between the link and the handle lever is moved past the dead center. 60

In testimony that I claim the foregoing as my own, I have hereto affixed my signature in the presence of two witnesses.

GEORGE T. BUDDLE.
